UNITED STATES PATENT OFFICE

2,386,608

STACK HUNG FLUSH TANK

Victor A. Hoffmann, Harvey, Ill.

Application June 12, 1942, Serial No. 446,695

16 Claims. (Cl. 4—68)

This invention relates to an improved stack hung flush tank and is a continuation in part of my copending application which matured into Patent No. 2,320,132.

The improved device of this invention includes a sealed tank provided with supporting means which are adapted to be affixed to a soil stack. The improved device is preferably sheathed in an insulating cover during installation. The cover prevents the formation of condensation on the surface of the tank and also functions as a muffler in reducing audible operating noises created within the tank.

In addition to the foregoing silencing means there is also provided mechanical means for quickly opening and closing the ball cock of a relatively large supply line. Moreover the improved device is designed and constructed to be positioned within a wall. Consequently, operating noises are reduced to a minimum.

One of the principal objects of advantage and importance of the improved device of this invention is the provision of means for using a relatively small float chamber which may be quickly filled after the water in the body of the shell or tank reaches a predetermined level. Accordingly, the time required for the closing movement of the float and associated ball cock in the supply line is correspondingly short.

Another object of advantage and importance resides in the provision of means for venting the sealed flush tank at some remote point. The vent, which provides the only opening between the interior of the tank and atmosphere, may be extended to an attic or some other unused portion of a house or building.

A further object of advantage and importance of the improved tank of this invention is the provision of means for utilizing a siphon in conjunction with a gravity feed ejector for quickly filling the small float chamber.

Another object of importance is the provision of means for positioning a hush box in the discharge passageway of the tank and providing means for venting the hush box through a vent tube. The hush box includes means for providing a water seal which tends to prevent the passage of noise through the tank discharge pipe.

Still another object of importance and advantage of the present invention resides in the provision of means for securing the improved device to a stack. Accordingly, when the improved tank is associated with a stack hung bowl, the entire plumbing fixture is supported independently of the framework of the house or building in which it is positioned.

An additional object of advantage and importance is the provision of means for supplying additional water to the float chamber after the

ball cock is closed to increase the holding and closing pressure.

Still another object of advantage of the improved device of this invention is the provision of means for utilizing a siphon as a passageway for emptying the tank and the small float chamber, in conjunction with a Douglas valve for starting the siphonic action.

A further point of advantage and importance is the provision of means for positioning a receiving and refill chamber in the upper portion of the improved tank of this invention.

Still another object of importance is the provision of means for inspecting the interior of the improved tank by the removal of a closure member from the front surface thereof.

Additional objects of advantage and importance will become apparent as the following detailed description progresses, reference being had to the accompanying drawings, wherein:

Fig. 1 is an elevational view of a stack hung sealed flush tank which embodies the invention, parts thereof being broken away.

Fig. 2 is a horizontal section taken on line 2—2 of Fig. 1, looking in the direction indicated by the arrows.

Fig. 3 is a vertical section taken on line 3—3 of Fig. 1, looking in the direction indicated by the arrows.

Fig. 4 is a slightly enlarged section of a fragmental portion of the device taken on line 4—4 of Fig. 2, looking in the direction indicated by the arrows.

Fig. 5 is a front elevational view of a slightly modified construction of the invention, parts thereof being broken away.

Fig. 6 is a vertical section taken on line 6—6 of Fig. 5 looking in the direction indicated by the arrows.

Fig. 7 is a vertical section taken on the line 6—6 of Fig. 5 looking in the opposite direction.

Fig. 8 is a horizontal section taken on line 8—8 of Fig. 5.

As shown in the drawings: 45 The reference numeral 10 indicates generally the tank or shell of the improved device of this invention. In the preferred embodiment of the invention, the tank 10 comprises a sealed shell.

Formed in the front surface of the tank 10 is an inspection and adjustment opening 12. Positioned over the opening 12 is a closure 14. The closure 14 is preferably secured to the tank 10 by screws or bolts. However, it will be obvious that the closure 14 may be secured by any suitable means.

Projecting upwardly from the top of the tank 10, preferably adjacent one end thereof, is a vent connection and passageway 16. The vent passageway may be extended as desired by pipes 18.

Extending upwardly from the top of the tank

10 is a plurality of supporting lugs 20 which are adapted to be secured to a supporting arm 22. The supporting arm 22 is adapted to be secured to a stack 24, as is clearly shown in Fig. 1.

Positioned within the tank 10 at one end and near the bottom thereof is a substantially cylindrical float chamber 26. The float chamber 26 extends from a point near the bottom of the tank 10 upwardly as is best shown in Fig. 1.

Projecting outwardly and thence upwardly from a point closely adjacent the bottom of the float chamber 26 is a discharge pipe 28. Hingedly positioned to cover the upper end of the discharge pipe 28 is a check or gate valve 30. The check valve 30 is adapted to swing freely upon its pivot. Accordingly the water level within the float chamber 26 cannot be maintained higher than the water level within the tank 10 unless the water level in the tank is below the discharge end of pipe 28.

Extending into the tank 10 is a supply pipe 32. The supply pipe 32 is provided with a ball cock 34.

Operably secured to the ball cock 34 and extending to a point directly above the float chamber 26 is an operating arm 36.

Operably positioned within the float chamber 26 and connected to the operating arm 36 by means of a link 38 is a float 40. The float 40 is preferably mounted upon a guide member 42. The guide member 42 limits the movement of the float 40 to vertical travel.

It will be apparent from the foregoing that upward movement of the float and the left end of the operating arm 36 closes the ball cock 34 and downward movement of this portion of the arm 36 and the float 40 opens the ball cock.

Extending outwardly and upwardly from the ball cock 34 is a slightly enlarged continuation 32a of the supply line 32. Positioned on the end of the continuation 32a is a fitting 44. The fitting 44 is turned to a horizontal plane paralleling the top of the tank 10 as is best shown in Fig. 1. The intermediate portion 46 of the fitting 44 is expanded as is best shown in Figs. 1, 2 and 4. The expanded portion 46 of the fitting 44 extends downwardly, as is clearly shown in the drawings, to form a sump. The enlarged continuation 32a reduces pressure but does not lessen the volume of water as compared to pressure and volume below the ball cock 34.

Projecting downwardly within the expanded portion 46 of the fitting 44 is a baffle plate 48. The baffle plate 48 is adapted to direct incoming water downwardly into the expanded portion of the fitting.

Extending downwardly from the expanded portion 46 of the fitting 44 is an ejector tube 50. Each end of the ejector tube 50 may be restricted, as is best shown in Fig. 4, with the lower opening slightly larger than the upper opening.

Extending downwardly from the restricted portion of the fitting 44 is a refill tube 52. The refill tube 52 is in alignment with and is adapted to deliver water into a combination vent and overflow tube 54. The upper end of the tube 54 terminates at a point below the plane of the lower edge of the utility opening 12 as is clearly shown in Figs. 1 and 3.

Projecting downwardly from the terminal of the fitting 44 is a tube 56. Both the upper and the lower end of the tube 56 are open.

It is to be noted that water delivered into the horizontal member 44 in excess of the capacity of the ejector tube 50 will flow through both the refill tube 52 and the tank filling tube 56. Pres-

sure is not required to operate refill or any of the other tubes.

Positioned astride the wall of the float chamber 26 is a siphon 58. The discharge leg of the siphon 58 is positioned within the float chamber 26.

Extending from the siphon 58 to the ejector tube 50 is a tube 60. The tube 60 provides a means whereby air may be withdrawn from the siphon 58 and be discharged through the ejector tube 50.

The function of the air ejector 50 is to quicken the action of the ball cock 34 by starting the siphon 58 at a predetermined time thus quickly filling the small float chamber 26 and raising the float 40. This almost instantaneous closing of the ball cock 34 is desirable and of utmost importance. A slow acting ball cock is very apt to whistle and moreover, foreign matter in the water lodges in and adheres to the valve causing leakage. The quick acting ball cock eliminates the noise nuisance and provides higher efficiency.

Projecting downwardly from the tube 60 is an extensible tube 62. The extensible tube 62 is adapted to be adjusted at any desired height within its range.

The extensible tube 62, when its lower end is above the level of the water in the tank 10, provides an air inlet passageway leading to the ejector 50. When the lower end of the tube 62 is submerged the passage of air therethrough is barred. Consequently, action of the ejector tends to evacuate the siphon 58 through the tube 60.

Positioned on the floor of the tank and extending therethrough is an outlet passageway 64. A Douglas ball 66 is operably associated with the passageway as is best shown in Figs. 1, 2 and 3. The Douglas ball 66 is connected to an operating handle 68 through a link 70 and an operating arm 72. Proper movement of the handle 68 raises the Douglas ball from the outlet passageway 64.

Positioned on the bottom of the tank 10 directly beneath the discharge passageway 64 is a hush box 74. The hush box 74 provides a continuation of the discharge passageway 64.

Formed within the hush box 74 is a downwardly projecting center wall 76 which in operation forms a trap or water seal. Air trapped within the hush box 74 is vented through the overflow pipe 54. The discharge end of the hush box 74 is preferably provided with a flange 78 to which a continuation 80 may be secured.

The flange 78 is provided with a downwardly extending member 79 as is best shown in Figs. 1 and 5. This construction permits the extended portion to be telescoped within a counterpart, as shown in Fig. 1, and provides a self aligning, leakproof and substantially foolproof joint. The weight of the tank alone upon the flanged portion of the fitting 80 is sufficient to form a watertight joint.

Operation of the above disclosed structure is substantially as follows: The device, after installation, is filled with water through the supply line 32. The water flows through the extension 32a into the fitting 44 and thence downwardly through the tubes 56, 52 and 50 into the shell 10. When the water in the shell reaches the end of the extensible tube 62 the passage of air therethrough is prevented. Consequently air is withdrawn from the siphon 58 through the tube 60 by operation of the ejector 50. When the air within the siphon 58 has become sufficiently rarefied the water rises therein and causes the siphon to operate, thus filling the float chamber 26.

The siphon 58 has a comparatively large capacity compared with the capacity of the relatively small float chamber 26. Consequently the float chamber 26 fills very rapidly. Accordingly, action of the float 40 and the connected ball cock 34 is also speedy.

When the device is flushed by operation of the handle 68 which raises the Douglas ball 66 the water within the shell 10 is discharged through the passageway 64. Air trapped within the hush box 74 is vented through the overflow tube 54 and may then be expelled from the tank through the vent 16. Water within the shell 10 and the float chamber 26 is maintained at a common level, while descending, through action of the gate valve 30. This valve functions to allow water to pass from the float chamber 26 into the shell 10 but prevents the passage of water from the shell 10 into the float chamber.

After the water level within the float chamber descends the float 40 also travels downwardly. This action opens the ball cock 34 and allows water to pass therethrough. When the water within the shell is nearly all discharged, the Douglas valve closes and the water from the supply line refills the shell. Concurrently with the refilling a small amount of water is directed through the refill tube 52 into the overflow pipe 54 and thence into and through the hush box 74. This water refills the bowl, not shown.

When the water level within the float chamber is sufficiently high to cut off the ball cock 34 additional water is still within the expanded portion 46 of the fitting 44. The flow of this additional water from the fitting through the ejector tube 50 continues the siphon 58 in action thus slightly raising the water level in the float chamber 26. This raising of the water level in the float chamber exerts an extra pressure on the ball cock and insures perfect closing. When the expanded portion 46 of the fitting 44 has emptied itself all action with the shell 10 ceases and the flush tank is ready for the next flushing operation.

In the slightly modified construction of the improved device of this invention as shown in Figs. 5, 6, 7 and 8, the shell 10a is relatively narrow in respect to its length. This construction has been designed for installations where an increased volume is desired over the volume of the shorter tank of the preferred embodiment.

Formed in the shell 10a is an opening 12a which is adapted to be employed for inspection and adjustment purposes. Secured to the shell 10a covering the opening 12a is a closure member 14a. The closure member 14a may be secured in place by any suitable means.

Positioned on the upper portion of the shell 10a is a vent 16a. The vent 16a may be threaded to receive a continuation, such as a pipe or the like.

Extending upwardly from the tube of the shell 10a is a pair of lugs 20a. The lugs are adapted to be utilized for securing the shell to a stack or other supporting element.

Positioned within the shell 10a is a float chamber 26a. The float chamber 26a is preferably positioned at one end of the shell 10a as is best shown in Figs. 5 and 8.

Extending outwardly and thence upwardly from a point closely adjacent the bottom of the float chamber 26a is an adjustable pipe 28a. The float pipe 28a forms a passageway into the float chamber 26a and thus provides a means for filling the float chamber from water within the shell 10a.

Positioned within the float chamber 26a is a float 30a. Movement of the float 30a is restricted to vertical travel.

Extending into the shell 10a is a supply line 31a. Positioned in the supply line 31a is a ball cock 34a. The ball cock 34a is operatively connected through the operating arms 36a and the standard 38a to the float 30a. Movement of the float 30a operates the ball cock 34a. Positioned within the shell 10a closely adjacent the top thereof is a chamber 40a. Extending downwardly from the chamber 30a is a discharge pipe 42a. The upper end of the discharge pipe 42a extends to a point well above the floor of the chamber 40a and the pipe is perforated 41a as is clearly shown by the dotted lines in Fig. 5.

Projecting downwardly from the chamber 40a is a refill tube 43a. The lower end of the refill tube 43a is telescoped within a vent pipe 44a, as is best shown in Figs. 5 and 6.

Extending upwardly from the ball cock 34a to a point within the chamber 40a is a continuation 46a of the supply line 32a. Water passing through the supply line 32a and the ball cock 34a is delivered into the chamber 40a.

Positioned within the shell 10a as is clearly shown in the drawings is a siphon 48a. The siphon 48a has an intake leg 50a positioned slightly above the floor of the shell 10a. An auxiliary leg 52a opens into the float chamber 26a. The discharge leg 54a of the siphon 48a extends through the floor of the shell 10a as is best shown in Figs. 5 and 7. The siphon 48a functions as an overflow and the lower interior surface of the bend therein is positioned below the plane of the lower edge of the utility opening 12a as is best shown in Figs. 5 and 6.

Disposed on the discharge leg 54a of the siphon 48a at a point above the discharge end thereof is a Douglas valve 56a. Surrounding the Douglas valve is an inverted bell 58a. The bell 58a functions to provide a water seal when the water level within the shell 10a drops below the Douglas valve. This water seal prevents leakage of air into the siphon to prematurely interrupt its action.

Joined to the front of the shell 10a directly beneath the discharge leg 54a of the siphon 48a is a hush box 60a. The hush box 60a is similar in construction to the hush box 74 shown in the preferred embodiment.

Operation of the modified form of the invention is substantially as follows: The device is positioned in place and after interior adjustments are made the utility door 14a is positioned in place. The water is then turned on and enters through the supply line 32a. The water is conveyed into the chamber 40a and as the water level rises above the upper end of the tube 42a it overflows into the shell 10a. A portion of the water is directed from the chamber 40a through the refill tube 43a into the vent tube 44a and thence into the hush box 60a.

When the water level within the shell rises to the top of the adjustable pipe 28a water is directed into the float chamber 26a. The float chamber 26a having a relatively small volume quickly fills. Thus the float action and the associated ball cock action is rapid. After the ball cock is completely closed the water from the chamber 40a drains through the perforation 41a and the refill tube 43a. The additional water delivered through the perforation 41a raises the level in the tank 10a and exerts an increased pressure on the ball cock 34a. The device is now ready for flushing.

Flushing is accomplished by opening the Douglas valve 56a. Water pours through the valve into the discharge leg of the siphon. This action tends to rarify the air in the upper portion of the siphon 48a and when the water level has receded sufficiently so that the Douglas valve is drawn to its seat, siphonic action is immediately started. The fall of the water level within the tank and within the float chamber is balanced by atmospheric pressure. As the water in the tank is withdrawn the float 30a lowers and opens the ball cock 34a.

It will be apparent from the foregoing that herein is provided a compact and highly efficient flush tank which may be positioned within a conventional wall or if so desired, positioned outside of a wall.

It will be further apparent that the modified form of the device with its greater depth and greater pressure is no harder to operate (raise the Douglas ball) than is the preferred embodiment. The high positioning of the Douglas ball in the tank eliminates excessive weight and pressure on top of the ball.

It will also be apparent from the foregoing that herein is provided an improved flush tank which, because of its peculiar and distinctive construction tends to eliminate long drawn out operating noises which customarily are associated with conventional devices.

It will also be apparent to those skilled in the art to which the device appertains that numerous changes in design and construction may be made without departing from the spirit or scope of the invention. Accordingly, the patent granted hereon is not to be limited to the precise embodiment here shown nor in any other manner except as is necessitated by the terminology of the appended claims when given the range of equivalents to which they may be entitled.

I claim as my invention:

1. In a flush tank, an enclosed shell having a valved outlet, a valved supply line extending into said shell, a float chamber positioned within said shell, a float operably positioned within said float chamber, said float being operably joined to said supply line, siphon means for filling the float chamber after the water in the shell reaches a predetermined level, means operable to maintain the discharge end of said siphon sealed against the passage of air thereinto when the water in the shell is discharged, and means for discharging the water from the float chamber and the shell in unison.

2. In a flush tank, a shell having an inspection opening therein, a closure removably positioned over said opening, a vent passageway extending from the interior of said shell to atmosphere, a valved outlet leading from said shell, said vent and said outlet providing the only exits from said shell, a valved supply line leading into said shell, a float chamber positioned within said shell, the volume of said float chamber being considerably less than the volume of said shell, a float positioned within said float chamber, said float being operatively linked to said valved supply line, siphon means connecting said chamber and said shell, means for rarifying the air in said siphon means to facilitate siphonic action, and an additional passage connecting said chamber with said shell.

3. In a flush tank, a shell having a valved outlet, a float actuated valved supply line extending into said shell, a float chamber positioned within said shell, a float positioned within said chamber,

ber, said float being connected to said valved supply line, siphon means for filling said float chamber from said shell when the water therein reaches a predetermined level, inlet actuated means for evacuating air from said siphon, a valved passageway extending from said chamber into said shell, said passageway being positioned near the bottom of said chamber, said valved passageway providing means whereby water is prevented from passing from the shell into the chamber but may pass from the chamber into the shell, said passageway being disposed to retain a substantial portion of the water within said chamber, and means for manually operating said valved outlet.

4. A stack hung flush tank comprising a shell, a valved supply line extending into said shell, a valved outlet extending from said shell, a float chamber positioned within said shell, valved means for filling said shell, means for filling said float chamber, means for emptying said shell and a portion of said float chamber concurrently, said filling and said emptying means comprising a siphon and a second passage, and means for withdrawing air from said siphon to facilitate siphonic action.

5. A stack hung flush tank comprising a shell, a supply line extending into said shell, a float actuated valve connected to said supply line, the delivery portion of said supply line extending upwardly to a point above said valve, the portion of supply pipe above said valve being larger in cross section than the portion of pipe below said valve, a portion of the enlarged pipe being expanded, said expanded portion being depressed to form a sump, a plurality of tubes extending downwardly from said enlarged pipe, a vent leading from the interior of said shell to atmosphere, a valved discharge passageway extending through the bottom of said shell, said discharge passageway including a pipe having a connection flange near the free end thereof to provide means for making a telescoped connection with an extension therefor, and manual means for operating said valved discharge passageway.

6. In a stack hung flush tank, a shell having a utility opening therein, a closure removably positioned over said opening and in watertight association with said shell, means for securing said shell to a stack, a valved supply line extending upwardly into said shell, the valve in said supply line being positioned intermediate the top and bottom ends of said upwardly extending supply line, means for substantially reducing the pressure and the speed of flow of water between the valve and the outlet end of the supply without diminishing the volume of delivery into the shell, a float chamber positioned within said shell, a float operably positioned within said float chamber, said float being operably connected to said valved supply line, means for timing the starting of the filling of said shell and said float chamber at different intervals, a valved discharge passageway leading from said shell, means for discharging the water from the float chamber concurrently with the discharge of water from the shell, and manually operated means for operating said valved discharge passageway.

7. In a flush tank, a substantially rectangular body, an inspection opening in one face of said body, said opening being above the normal water level of the device, a cover removably positioned over said opening, a vent passageway extending through the upper wall of said body, a valved outlet extending through the bottom of said body,

a cylindrical float chamber positioned within said body, a float guide extending upwardly from the floor of said float chamber, said guide functioning to limit the movement of a float associated therewith to vertical travel, a float operably positioned upon said guide, a valved supply line extending into said body, said valved supply line being operatively connected to said float providing means for admitting water into said body, means for quickly filling the float chamber after the water in body reaches a predetermined level, and automatically operated valve means for maintaining the water within said float chamber and said body at a common level as it is discharged therefrom.

8. In a flush tank, a shell having a valved outlet, a valved supply extending into said shell, a float chamber positioned within said shell, siphon means for filling said float chamber after the water in the shell reaches a predetermined level, and automatically operated valve means for allowing the water in the chamber to escape into the shell as the water in the shell is discharged.

9. In a flush tank, a shell, a utility opening in said shell, a closure positioned over said opening, a float chamber positioned within said shell, a valved discharge passageway near the bottom of said chamber, said passageway comprising an outwardly and thence upwardly turned tubular member, and siphon means for filling said float chamber.

10. In a flush tank, a shell, a vent passageway extending from the interior of said shell to atmosphere, a valved supply line extending into said shell, a float chamber positioned within said shell, means for filling said float chamber from said shell after the water therein reaches a predetermined level, a float positioned within said float chamber, said float being connected to operate said valved supply line, siphon means for discharging the water from said shell and said float chamber, and means for rarifying air in said siphon means to facilitate siphonic action.

11. In a flush tank, a shell, a vent passageway extending from the interior of said shell to atmosphere, a valved supply line extending into said shell, a float chamber positioned within said shell, adjustable means for filling said float chamber from said shell after the water therein reaches a given level within a predetermined adjustment range, a float positioned within said float chamber, said float being connected to operate said valved supply line, a siphon positioned within said shell, the discharge leg of said siphon being positioned to empty into a discharge passageway beneath said shell, a valve positioned in the discharge leg of said siphon, means for forming a water seal around said valve, and means connected with said siphon for emptying said float chamber.

12. In a flush tank, a shell, a vent passageway extending from within said shell to atmosphere, a valved outlet positioned at the bottom of said shell, an adjustment and inspection opening in said shell, said opening being disposed to permit inspection and adjustment within the operably filled shell, a closure removably secured over said opening, a float chamber positioned within said shell, the area of said float chamber being considerably less than the area of said shell, a float positioned within said float chamber, a valved supply line extending into said shell, said supply line being operatively connected to said float, means for quickly filling said float chamber after the water in said shell reaches a predetermined

level, and means for emptying said float chamber and said shell concurrently, said last named means comprising a siphon having an inlet leg disposed to feed from said shell and a second inlet leg disposed to feed from said float chamber.

5 13. In a flush tank, a shell having a valved outlet, a valved supply line extending into said shell, a float chamber positioned within said shell, a float operably positioned within said float chamber, said float being operably joined to said supply line, siphon means for filling said chamber after the water in said chamber reaches a level within a predetermined range, said last named means including supply line actuated means for evacuating the air from the upper portion of said siphon means.

10 14. In a flush tank, a shell having a valved outlet, a valved supply line extending into said shell, a float chamber positioned within said shell, a float operably positioned within said float chamber, said float being operably joined to said supply line, siphon means for filling said chamber after the water in said chamber reaches a level within a predetermined range, said last named means including a sump in said supply line, a tube extending downwardly from said sump, a restriction in the intermediate portion of said tube, a second tube extending from the upper part of said siphon means to a point in said first named tube slightly below said restriction, said first and said second tubes providing means whereby gravitational flow of water through said first tube evacuates air from said siphon through said second tube thus activating said siphon.

15 15. A stack hung flush tank of the character described comprising, a shell, said shell being substantially rectangular in shape and having a utility opening formed in the front wall thereof closely adjacent the top of said shell, a closure member positioned over said opening and in fluid tight association with said shell, a hush box positioned on the bottom of said shell and forming a discharge therefor, overflow means extending from said hush box upwardly into said shell, the upper terminal of said overflow being disposed to permit overflow from the shell to occur when the level of liquid in the shell is below the lower edge of said utility opening, a vent passageway leading from the interior of the shell to atmosphere, a valved supply line extending into said shell, automatically operated means controlling said valved supply line and including a float chamber positioned within said shell, adjustable means controlling the filling of said float chamber when the water from said supply line fills the shell to a level within a predetermined range, and valve means controlling discharge from said shell.

60 16. In a stack hung flush tank of the character described comprising, an enclosed shell having a front wall, a utility opening in said front wall, a closure removably positioned over said opening and in sealed engagement with said shell, means for venting said shell to a remote location, 65 an outlet having a trap therein positioned at the bottom of said shell, automatically operated valved means for supplying said shell, overflow means extending from the interior of said shell to said outlet, the upper portion of said overflow means being disposed to permit removal of said closure and visual inspection of the interior of the shell during flushing and filling operation of said tank, and valved means for controlling flow from said shell.
